UNITED STATES PATENT OFFICE.

ALFRED L. SOHM, OF CHICAGO, ILLINOIS, ASSIGNOR TO SOHM ELECTRIC COMPANY, OF CHICAGO, ILLINOIS, A CORPORATION OF ILLINOIS.

SECONDARY-CLOCK SYSTEM.

1,302,604.

Specification of Letters Patent.

Patented May 6, 1919.

Application filed May 21, 1917. Serial No. 169,874.

To all whom it may concern:

Be it known that I, ALFRED L. SOHM, a citizen of the United States, residing at Chicago, in the county of Cook and State of Illinois, have invented a certain new and useful Improvement in Secondary-Clock Systems, of which the following is a full, clear, concise, and exact description, reference being had to the accompanying drawings, forming a part of this specification.

The present invention relates to a secondary clock system.

Heretofore in the art it has been found very difficult to keep the secondary clocks in exact synchronism with the master clock because of the occasional occurrence of "double" contacts. No matter how carefully constructed the contact mechanism of the clock may be, double contacts will occur, even if at infrequent intervals. This may be due to the fact that the springs vibrate, or it may occur because of the slight reverse rotation of the minute shaft which occurs through the action of the escapement. This reverse rotation, which occurs at the end of each beat, may bring the moving contact either to the point where it just touches the stationary contact and is again withdrawn or it may bring the contact to the point where it is just leaving the stationary contact, where the double contact will occur.

The object of this invention is to provide an electrically operated secondary clock actuating system, which shall be proof against double or false impulses, and which shall be simple in construction and positive in action.

The invention also aims to simplify clock construction by providing novel means and by eliminating fine and coarse adjustment which heretofore have been found necessary.

In the accompanying sheet of drawings, I have illustrated an apparatus embodying the present invention. Figure 1 is a plan view of a relay mechanism used in the improved clock system.

Fig. 2 is a side elevation of the same.

Fig. 3 is a fragmentary detailed view, showing the manner in which the detent engages the armature of one of the electro-

magnets.

Fig. 4 is an enlarged detailed view showing the rear face of the armature shown in Fig. 3.

Fig. 5 is a circuit diagram of the system.

In Fig. 5 I have shown a plurality of sec-

ondary clocks which are operated by a master clock, not shown in the drawings but indicated diagrammatically by means of the time controlled shaft 7 bearing the cam 8. The shaft 7 may be the second hand arbor 60 of the clock or may be driven in unison therewith, as it is customary to advance the clock 6 upon the completion of each minute.

Cam 8 is snail shaped and bears a contact 9, which forms an intermediate step between 65 the outermost dwell 10 and the innermost dwell 11 of the snail cam. A pair of springs 12 and 13 are secured in a block of insulation 14 and suspended from a pivot 15 so that these springs may rise and fall with the 70 rotation of the cam. The spring 12 is made longer than spring 13 and the end of the spring 12 is slightly higher.

As the cam 8 rotates in a clockwise direction, the springs 13 and 12 successively 75 make contact with the step 9, which is connected by means of wire 16 to one side of the battery 17. The spring 13 is connected with one terminal of the electro-magnet 18, the other terminal of the electro-magnet 18 being connected to the other side of the battery 17. The spring 12 is connected to one terminal of the electro-magnet 19, the other terminal of this magnet being also connected to battery 17 so that contact of the 85 springs 13 and 12 with the contact step 9 of the cam energizes the magnets 18 and 19 in turn.

The armature 20, is pivoted at its lower edge at 21 by means of screws 22 passing 90 through lugs in the base 23 upon which both electro-magnets are mounted. An I-shaped spring 24 shown partly in dotted lines in Fig. 2 serves to retract the armature 20 from the electro-magnet 18 when it is in a 95 non-energized condition. The armature 20 bears a spring 25 which extends upwardly and registers with a contact screw 26 fastened in a yoke 27 secured to but insulated from the base 23. The spring 25 is provided 100 with a slot 28, through which passes a detent or catch 29, forming an extension of the armature 30 of the electro-magnet 19. A spring 31 tends to hold the detent 29 against the armature 20 as shown in Fig. 2 105 in order to hold the contact spring 25 against the stationary contact 26. The armature 20 has a notch or cut away portion 32 in which the end of the detent 29 rests when the armature 20 is in the retracted position. At this 110

time the contacts 25 and 26 are not in engagement. The notch 32 furnishes an incline over which the end of the detent 29 must pass before the contacts 25 and 26 can come into engagement and offers sufficient resistance to prevent the contacts being jarred together by accident.

The armature 30 is pivotally mounted on the standards 33 which also furnishes a support for the electro-magnet 18. Suitable binding posts, as shown in Figs. 1 and 2, are provided on the base 23 for the terminals of the electro-magnets and of the contacts. An adjusting screw 34 for adjusting the tension 15 of the spring 24, governing the armature 20, is also provided.

It can now be seen that as the cam 8 rotates in a clockwise direction, the spring 13 will drop off of the upper dwell 10 upon the 20 intermediate dwell 9 where contact will be made and the circuit for the electro-magnet 18 will be closed. The electro-magnet 18 attracts its armature 20 closing the contacts 25 and 26 which govern the circuit of the secondary clocks 6. When the armature 20 is attracted, the latch 29 holds the same in position to retain contacts 25 and 26 in engagement. As the cam 8 advances the spring 13 will drop off of the intermediate dwell 9 and 30 the spring 12 will make contact with said intermediate contact. The circuit of the release electro-magnet 19 is then closed and the armature 20 is released, the contacts 25 and 26 separating at this time under the influence of the spring 24.

The circuit of the clocks 6 remains closed for a definite period of time for each revolution of the cam 8, the period of time depending upon the spacing of the springs 12 40 and 13 but the same being invariably uniform. It has been found very difficult to avoid the making of double contacts in operating a master clock, due to the slight reverse rotation of the second hand arbor 7 in the ordinary master clock. If the break between the spring and the rotating contact occurs just at the point where the escapement gives a slight backward rotation to the shaft 7, the contact will first be made on the 50 forward movement of the escapement and then be broken on the slight reverse rotation, and in this manner two impulses will be sent when only one should have been transmitted to the secondary clocks.

55 A similar condition obtains if the rotating contact is just passing out of contact with the spring and the slight reverse rotation of the shaft 7 again brings the rotating contact against the spring, giving a double impulse. 60 The structure that I have shown not only avoids the above making of double contacts, but securely guards against any such action or any other accidental making of double contacts. When the spring 13 drops down 65 on the intermediate dwell 9, the slight re-

verse rotation, which might cause a break if the contact surface and the cam were cylindrical, cannot occur because the end of the spring 13 strikes against the radial wall of the cam. As soon as the spring 13 drops 70 off of the intermediate dwell 9, the spring 12 will be brought into engagement with the intermediate dwell 9 and any reverse rotation, which would tend to bring the spring 13 in contact with the contact 9, forming 75 the intermediate dwell would cause the end of spring 12 to strike the radial portion of the cam. It can be seen that double contacts are avoided but even if the same should be made, no false operation of the secondary 80 clocks would occur as the armature 20 of the circuit closing magnet 18 is held in attracted position by means of the detent 29 until it is positively released by the energization of the magnet 19. No matter how 85 many times the circuit may be made through the magnet 18 the contacts 25 and 26 will be operated only once until the released magnet 19 is energized and no matter how many energizations of the magnet 19 occur, 90 they are all ineffective for closing the contacts 25 and 26.

It will be apparent that numerous modifications will occur to those skilled in the art, all of which I consider to come within the spirit and scope of the present invention.

What I claim as new and desire to protect by Letters Patent is the following:

1. In a mechanism for controlling a secondary clock circuit, a rotatable snail cam, 100 constructed of insulation material, an electrical contact on the cam intermediate the high and the low dwells thereof, an electro-magnet for closing a secondary circuit, a latch for holding said circuit closed, a release magnet for opening said circuit, two spring contacts, one longer than the other adapted to drop in succession from the high dwell of the cam to the intermediate contact, the shorter contact adapted to energize the circuit closing magnet and the longer one to energize the release magnet, the springs adapted to engage the shoulder of the cam above the intermediate contact to prevent retrograde movement of the cam. 110

2. In a mechanism for controlling a secondary clock circuit, a master clock having a rotatable shaft, a snail cam having a non-conducting periphery and mounted upon said shaft, an electrical contact dwell on the cam intermediate the high and the low dwells thereof, two springs, one longer than the other adapted to successively drop from the high dwell to the intermediate contact and adapted thereby to successively energize 120 a secondary circuit closing magnet and a secondary circuit release magnet, the springs adapted to engage the shoulder of the cam between the contact and the high dwell to prevent retrograde movement of the cam. 125

3. In a clock system of the kind described, a master clock having a rotatable cam provided with a contact for controlling a secondary clock circuit, a pair of terminals one controlling a secondary circuit closing magnet and the other a secondary circuit opening magnet, said terminals adapted to successively close upon said contact as the cam rotates, and means coöperating with said 10 terminals to prevent retrograde movement of the cam immediately after the terminals close upon said contact.

4. In a clock system of the kind described, a master clock having a rotatable snail cam 15 with a contact for controlling a secondary circuit, a movable terminal adapted to drop upon said contact to close a secondary circuit as the cam rotates in one direction, and a shoulder on the cam above said contact 20 adapted to engage the end of the terminal to prevent retrograde movement of the cam, and a second terminal adapted to contact

with the contact on the cam as the first terminal leaves same to open the secondary circuit.

5. In a clock system of the kind described, a secondary circuit closing magnet having a spring held armature movable to secondary circuit closing position when the magnet is energized, a latch for retaining the armature in circuit closing position, a release magnet for releasing the armature to open the secondary circuit, a master clock having a snail cam for controlling the secondary circuit, an electrical contact on said cam, a terminal 35 for the closing magnet circuit and a terminal for the opening magnet circuit, the two terminals adapted to contact in succession with the contact on the cam to successively close their respective circuits for predetermined independent periods of time.

In witness whereof, I hereunto subscribe my name this 17th day of May A. D. 1917.

ALFRED L. SOHM.
